Primary Examiner — Dana Meyrow*(74) Attorney, Agent, or Firm* — Bojuan Deng(57) **CLAIM**

The ornamental design for bottle, as shown and described.

DESCRIPTION

FIG. 1 is a front perspective view of one embodiment of a bottle embodying the new design;

FIG. 2 is a front side elevation view thereof;

FIG. 3 is a rear side elevation view thereof;

FIG. 4 is a right side elevation view thereof;

FIG. 5 is a left side elevation view thereof;

FIG. 6 is a top plan view thereof and,

FIG. 7 is a bottom plan view thereof;

FIG. 8 is a front perspective view of another embodiment of a bottle embodying our new design;

FIG. 9 is a front side elevation view thereof;

FIG. 10 is a rear side elevation view thereof;

FIG. 11 is a right side elevation view thereof;

FIG. 12 is a left side elevation view thereof;

FIG. 13 is a top plan view thereof; and,

FIG. 14 is a bottom plan view thereof.

The evenly-dashed broken lines in the drawings illustrate the portions of the bottle that form no part of the claimed design. The dot-dash broken lines in the drawings define the bounds of the claim and form no part thereof.

1 Claim, 12 Drawing Sheets(56)
